METHOD OF AND MEANS FOR CHARGING
BAROMETRIC FEED DEVICES

Rallston M. Sherman, Glastonbury, Conn., assignor to The Silent Glow Oil Burner Corporation, Hartford, Conn., a corporation of Connecticut

Application April 20, 1932, Serial No. 606,509

12 Claims. (Cl. 158—40)

This invention relates to barometric feed devices of the type commonly employing a liquid-containing receptacle in which, despite withdrawal of liquid therefrom, a constant level is maintained by replenishment from a supply tank or reservoir in which a body of liquid is sustained by the maintenance therein of a sub-atmospheric pressure, the tank being so related to the receptacle through the maintenance of a communicating orifice, normally sealed by the liquid, that a supply of liquid in the receptacle is automatically replenished from the tank while preserving in the receptacle a substantially constant liquid level.

15 Barometric feed devices of this type are commonly used for the purpose of supplying liquid fuel to liquid fuel burners of the so-called combustion-tube type where liquid fuel is supplied by gravity from the constant level receptacle to the fuel grooves of the burner and there vaporized and burned with a suitable mixture of air. Such barometric feed devices usually comprise an inverted glass bottle, the open mouth of which is submerged or covered by the liquid fuel contained in an underlying constant level receptacle from which the liquid fuel is fed by gravity through a connecting feed pipe to the base of the burner, the bottle being removable from its support so that it can be placed right side up, 20 refilled and again replaced in its inverted position, when it becomes necessary to refill it or replenish its supply.

One of the objects of the present invention is the provision of means to replenish the supply of liquid in the tank or reservoir of a barometric feed device without the necessity of disturbing the position of the tank, and at the same time without disturbing to any substantial extent the level designed to be maintained in the constant 25 level receptacle.

In case of a barometric feed device employed for combustion tube burners such as have been referred to, it is highly desirable that a substantially constant liquid level be maintained. If the 30 level is unduly raised, the burner tends to become flooded, and if substantial variations in level occur while the burner is in operation, the action of the burner is seriously affected either by a raising or a lowering of the liquid level in the constant level receptacle. The present invention provides means for replenishing the tank or reservoir of such a burner without removing the tank or reservoir from its support, and such reservoir, if desired, may be permanently established 35 in position and may also be materially increased

in size, since during the normal use of the burner no occasion will arise for lifting or moving the reservoir from its established position. Since no substantial disturbance in the level of the liquid fuel takes place during such replenishing process, 5 the tank may be refilled irrespective of whether the burner at the same time is in or out of operation and without disturbing or impairing the action of the burner during the replenishing process.

10 The invention will be best understood by reference to the following description when taken in connection with the accompanying illustration of one specific embodiment thereof, while its scope will be more particularly pointed out 15 in the appended claims.

In the drawing,—

Fig. 1 is an elevation, partially in section and partially diagrammatic, showing the principal operative parts comprising the illustrative embodiment of the invention;

Fig. 2 is an enlarged detail in section showing one end of the pump with the check valves employed thereat; and

Fig. 3 shows a modified form of the pumping 25 arrangement.

Referring to the drawing, there is shown for illustrative purposes a barometric feed device employed for the purpose of supplying liquid fuel to a combustion tube burner, such fuel being 30 herein referred to as oil for the purpose of description. Such device comprises a constant-level, bowl-shaped receptacle 5 having an enlarged upturned mouth formed by the sides 7 through which it is supported on the floor by the 35 legs 9 and within which mouth is supported the tank or reservoir 11. The latter may be of glass, metal, or any other suitable material capable of maintaining a partial vacuum or sub-atmospheric pressure in the upper part of its interior, which 40 for brevity (though somewhat inaccurately) may be referred to as the "vacuum space". The tank may be removable from its support or, if desired, permanently fixed in position. The bottom of the tank is herein provided with an open mouth 45 13 which projects downwardly into the oil carrying part of the bowl where the oil at its normal level provides a liquid seal for the mouth. The liquid in the bowl is subject to atmospheric pressure through the orifices 15—15.

50 Assuming the tank filled or partially filled, the oil supply in the bowl is maintained at a constant level by conditions well understood in the art. So long as the mouth 13 is subject to the liquid seal, the body of oil in the tank 11 is held 55

sustained by the difference between the external atmospheric pressure and the sub-atmospheric pressure in the vacuum space. As oil is withdrawn from the bowl, tending to drop the level of 5 the oil therein, the liquid seal is broken and air enters, passing to the upper part of the tank and permitting escape through the mouth into the bowl of a sufficient quantity of oil to maintain the level re-seal the mouth, and re-establish conditions of equilibrium.

10 The burner 17, which typifies any of the usual forms of combustion tube burners, such, for example, as that disclosed in my prior Patent No. 1,676,223, has its base connected through the 15 burner supply pipe 19 with the bottom of the bowl 5, there being also provided the intervening controlling valve 21. The operation of the burner depends in large measure on the proper alignment of the burner grooves with relation to 20 the level of the oil in the tank 5, as is represented by the dotted line 23, and on the maintenance of the oil level to correspond to that line.

25 To replenish the supply of oil in the tank, while maintaining substantially the same liquid level in the receptacle, means are provided for adding liquid to the liquid body of the tank and bowl, herein by forcibly introducing liquid into the tank, and concurrently withdrawing air from 30 the upper part thereof to reduce the pressure therein. This operation may be carried out in various ways, but herein there is provided a pump which may be either manually or power operated, the same comprising a cylinder 25 with 35 contained piston 27 and piston rod 29. One end of the pump cylinder communicates through the passage 31 and the inwardly opening check valve 33 (see Fig. 2) with an air suction pipe 35 which extends through a suitably packed orifice in the bottom of the bowl, and up through the bowl 40 into the tank 11, its open end being located near the top of the vacuum space therein. The same end of the pump cylinder also communicates through the passage 37 and the outwardly opening 45 check valve 39 with an air discharge connection 41.

50 The opposite end of the pump cylinder is connected through a passage and an outwardly opening check valve (similar to the check valve 39) with an oil delivery pipe 43 which extends through a suitably packed orifice in the bottom of the bowl to some point where it is capable of adding the oil discharged thereby to the liquid body 55 either by delivering it into the bowl or into the space within the tank 11. Preferably, though not necessarily, the pipe 43 extends into the body of the tank for a sufficient height so that the delivery of oil by the pump will not act to disturb by agitation the level of the oil in the constant 60 level receptacle. The same opposite side of the pump cylinder communicates through an inwardly opening check valve (similar to the check valve 33) with an oil suction pipe 45, which latter extends to approximately the bottom of an oil 65 receptacle from which the main oil supply is derived, this being herein diagrammatically represented as a main oil tank which may be fixed or portable and located at any desired position with relation to the barometric feed device and to 70 the pump.

75 When it is desired to replenish the supply of oil in the reservoir or tank 11, the pump is actuated by reciprocating the piston 27. Movement of the piston in one direction serves to draw oil from the tank 47 into the oil end of the pump

cylinder and at the same time to expel the air from the opposite or air end of the cylinder. The next succeeding movement of the piston in the opposite direction serves to withdraw a definite measured volume of air into the air end of the pump cylinder from the vacuum space of the tank 11, and simultaneously to replace it by the forcible introduction of a definite measured volume of oil expelled from the opposite or oil end of the pump cylinder. The refilling action is then continued by further reciprocations of the pump piston until the tank 11 is filled or the desired replenishment is effected.

10 While a single pump cylinder is thus provided, through the valve arrangement in opposite ends of the cylinder, two positive displacement pumping means are actually embodied in this double acting pump, one for pumping oil and the other for pumping a definitely related volume of air, and, if desired, these two pumping means might 15 be embodied in separate structures suitably connected for concurrent operation.

15 The removal from the vacuum space (at the sub-atmospheric pressure then established therein) of a volume of air less than, or merely equal to, the volume of oil concurrently introduced would cause some alteration of the oil level in the bowl, since, to support the added height of the liquid body without change in the level, a still 20 lower sub-atmospheric pressure must be established. If, as would usually be the case, the quantity of oil in the bowl 5 is substantially less than that in the tank 11, the oil level would be subject to a substantial rise if the volume of air withdrawn were no greater than that of the oil entered.

25 If, on the other hand, too great a volume of air is withdrawn, the mean level will not be altered for the oil body in the tank will tend first to rise, uncover the mouth and break the liquid seal, this being followed by the admission to the vacuum space of sufficient air to correct for any excess withdrawn and then by the lowering of the oil body, the closing of the liquid seal and the 30 re-establishment of equilibrium. Although, under these conditions, the mean level is kept the same, this action may be accompanied by some agitation of the oil in the bowl.

35 Accordingly, it is desirable to withdraw a volume of air somewhat greater than the volume of oil introduced, and preferably such an excess of air as will itself reduce the sub-atmospheric pressure to a point which will maintain the body of oil in the tank without any substantial tendency either to rise or descend with relation to the 40 bowl. These conditions may be met by a variety of means. In the apparatus described, not only is the air withdrawn simultaneously with the introduction of the oil, but the volume of air withdrawn may be adjusted to exceed that of the oil 45 introduced by exactly the required amount.

50 For this purpose, the air capacity of the pump exceeds the oil capacity by an amount sufficient to yield the excess required for the liquid to be dealt with. This is due to the fact that the capacity of the oil end of the cylinder is reduced by the space occupied by the piston rod 29. The air suction pipe 35 is also slightly larger than the oil delivery pipe 43, there being provided, however, in the pipe 35, between the bowl and the 55 pump, a reducing valve 51 by which, if desired, the amount of air withdrawn contemporaneously with the entering of each charge of oil may be cut down to the amount which will not only prevent any rise of oil level in the bowl, but, if de- 60

sired, may be such as to prevent any agitation of the oil in the bowl due to too great a withdrawal of air. This provides means whereby the apparatus may be readjusted when required to deal with oils or other liquids of different specific gravities, the heavier the liquid the greater the amount of air required to be withdrawn in order to maintain the equilibrium of level conditions referred to.

10 The oil and air pipes 35 and 43 may, if desired, be provided beneath the bowl with shut-off valves (not shown).

In Fig. 3 there is shown a modified arrangement of the pumping apparatus by which substantially the same results may be accomplished. There is here provided two rotary pumps, one an oil pump 53 and another an air pump 55, mounted side by side to be driven by the same electric motor 57. Each pump is of the positive 20 displacement type, such, for example, as the well-known eccentric vane construction, that is to say, capable of discharging in each cycle of operation a definite measured volume of fluid, and of such relative capacities, either through 25 inherent design or through the provision of suitable controlling devices, that in one cycle of operation the volume of air withdrawn by the air pump is slightly greater than the volume of oil discharged by the oil pump. The air pump 30 has a discharge connection 41', similar to 41 in Fig. 1, and is connected to an air suction pipe 35' which enters the tank in the same manner as the pipe 35. The oil pump has an oil suction pipe 45' leading to the main oil tank 47, similar 35 to the pipe 45, and an oil discharge pipe 43' connected to the bowl or tank in the same manner as the pipe 43 in Fig. 1.

While the illustrative arrangement, such as is shown in Fig. 1, provides ideal conditions for the maintenance of the level equilibrium as explained, it is not essential for such purpose that any given charge of liquid be added to the main liquid body in exact coincidence with the withdrawal of a balancing volume of air, so long as the aggregate volume of liquid added and the aggregate volume of air withdrawn are such as to cause no substantial change in the level of the liquid in the bowl either during or at the close of the process of replenishment.

50 Charges of liquid might be entered and volumes of air withdrawn in alternation in such small amount as to cause no appreciable fluctuation in the liquid level during the process of replenishment and no appreciable change in the liquid level at the termination of such replenishment. For example, in the case of the rotary pumps disclosed in Fig. 3, these might be turned slowly by hand instead of through an electric or other motor, under which conditions the volume 55 of liquid entered and the volume of air withdrawn at each impulse would be so relatively small that no appreciable fluctuation in the liquid level would occur. Nor, so long as the two pump means are operated in timed relation and their volumetric capacities are properly related, is it necessary that the impulses of one should coincide exactly with the impulses of the other, but such impulses might be overlapping or in alternation.

On the other hand, charges of liquid might 70 be entered and volumes of air withdrawn in alternation and of greater volume than those represented by each impulse of the eccentric vane pump but with such rapidity that the unbalancing action of an entered liquid charge would have 75 no opportunity to act to upset the equilibrium

before the balancing or corrective action of the air withdrawal takes place.

Accordingly, in referring to the "concurrent" or "coincident" addition of the liquid and withdrawal of the air, or concurrent or coincident operation of the pumps, I intend to include such timing of the liquid addition and air withdrawal as will provide for replenishment without substantial changes, either temporary or final, in the level of the liquid in the bowl.

10 While I have herein shown and described for the purpose of illustration one specific application of the invention and the constructional details of one embodiment thereof, it is to be understood that extensive deviations may be made 15 from the form, construction and relative arrangement of parts and that various other applications of the principles herein set forth may be made, all without departing from the spirit of the invention.

20 I claim:

1. The combination with a constant level barometric liquid feed device, which body of liquid is sustained by the maintenance of a sub-atmospheric pressure space, of replenishing means 25 comprising a main liquid supply tank, a liquid pump, an intake connection between the pump and said supply tank, a discharge connection from the liquid pump to said barometric feed device, an air pump having an intake connection 30 opening into said sub-atmospheric pressure space, a discharge connection opening into the atmosphere, and means for operating said liquid and said air pumps simultaneously to supply liquid to the device, and simultaneously withdraw air therefrom in such relative volume and for such relative time as to insure against rise of the constant level maintained thereby.

2. The combination with a constant level barometric liquid feed device, which body of liquid is sustained by the maintenance of a sub-atmospheric pressure space, of replenishing means comprising pumping means for adding to said body a measured volume of liquid, and pumping means for concurrently withdrawing from said space a greater volume of air at least sufficient to compensate for the measured volume of liquid.

3. The combination with a constant level barometric liquid feed device, which body of liquid is sustained by the maintenance of a sub-atmospheric pressure space, of replenishing means comprising a double acting pump having connections communicating with the sub-atmospheric pressure space and having other connections communicating with said barometric feed device for pumping and adding liquid to said liquid body simultaneously with the said withdrawal of air from said space and in amount small enough to be compensated for by the withdrawn air.

4. The combination with a barometric liquid feed device comprising a feeding tank, the upper part of which is hermetically closed to permit the maintenance of a sub-atmospheric pressure to sustain therein a body of liquid, of a constant level receptacle fed therefrom and communicating with the lower part of said tank through an orifice normally submerged in the liquid of said receptacle and providing a liquid seal thereat, means for replenishing said tank comprising an air ejection conduit communicating with the sub-atmospheric pressure space in said tank, a liquid discharge conduit extending into said tank above said liquid seal, and pumping means connected to said ejection conduit and said discharge conduit for concurrently withdrawing air from said

- space and adding liquid to said liquid body in an amount compensated for by the withdrawal of air.
5. The combination with a barometric liquid feed device comprising a feeding tank, the upper 5 part of which is hermetically closed to permit the maintenance of a sub-atmospheric pressure to sustain therein a body of liquid, of a constant level receptacle fed therefrom and communicating with the lower part of said tank through an orifice 10 normally submerged in the liquid of said receptacle and providing a liquid seal thereat, means for replenishing said tank while maintaining substantially the same liquid level in the receptacle, the same comprising means to add a 15 volume of liquid to said liquid body, and means to concurrently withdraw from the sub-atmospheric pressure space of said tank a volume of air which at the pressure there prevailing is greater than the said volume of liquid.
20. 6. The combination with a barometric liquid feed device comprising a feeding tank, the upper part of which is hermetically closed to permit the maintenance of a sub-atmospheric pressure to sustain therein a body of liquid, of a constant 25 level receptacle fed therefrom and communicating with the lower part of said tank through an orifice normally submerged in the liquid of said receptacle and providing a liquid seal thereat, means for replenishing said tank while maintaining substantially the same liquid level in the receptacle, the same comprising means to add liquid 30 to the said liquid body, and means concurrently to withdraw air from the upper part thereof to reduce the pressure therein.
35. 7. The combination with a barometric liquid feed device comprising a feeding tank, the upper part of which is hermetically closed to permit the 40 maintenance of a sub-atmospheric pressure to sustain therein a body of liquid, of a constant level receptacle fed therefrom and communicating with the lower part of said tank through an orifice 45 normally submerged in the liquid of said receptacle and providing a liquid seal thereat, means for replenishing said tank comprising positive displacement pump means for withdrawing air from said sub-atmospheric pressure space, and positive displacement pumping means for concurrently adding liquid to said liquid body.
50. 8. The combination with a barometric liquid feed device comprising a feeding tank, the upper
- part of which is hermetically closed to permit the maintenance of a sub-atmospheric pressure to sustain therein a body of liquid, of a constant level receptacle fed therefrom and communicating with the lower part of said tank through an orifice 5 normally submerged in the liquid of said receptacle and providing a liquid seal thereat, means for replenishing said tank comprising positive-displacement, air-pumping means, positive-displacement, liquid-pumping means, and means 10 connecting said pumping means to operate the same to move their fluids concurrently.
9. The combination with a barometric liquid feed device comprising a feeding tank, the upper part of which is hermetically closed to permit 15 maintenance of a sub-atmospheric pressure to sustain therein a body of liquid, of a constant level receptacle fed therefrom and communicating with the lower part of said tank through an orifice normally submerged in the liquid of said 20 receptacle and providing a liquid seal thereat, means for replenishing said tank while maintaining substantially the same liquid level in the receptacle, the same comprising means to add liquid to the said liquid body, and means concurrently 25 to withdraw air from the upper part thereof to reduce the pressure therein.
10. The method of replenishing the liquid in a constant level barometric feed device, in which a body of liquid is sustained by the maintenance 30 of a sub-atmospheric pressure space, which consists in adding to said body a volume of liquid and concurrently withdrawing a volume of air which, at the pressure prevailing in said space, is greater than the volume of liquid added.
11. The method of replenishing the liquid in a constant level barometric feed device, in which a body of liquid is sustained by the maintenance 35 of a sub-atmospheric pressure space, which consists in adding to said body a volume of liquid, concurrently withdrawing by eduction a volume of air definitely related to said volume of liquid, thus preserving substantially constant the level maintained by said device.
12. The method of replenishing the liquid in a constant level barometric feed device, in which a body of liquid is sustained by the maintenance 40 of a sub-atmospheric pressure space, which consists in adding to said body a definitely measured volume of liquid, and concurrently withdrawing 45 by eduction a definitely measured volume of air.

RALLSTON M. SHERMAN.
